RECLINING CHAIR

Ralph H. Ellsworth, Willoughby, Ohio, assignor to
The Wolwin Chair Company, Willoughby, Ohio

Application October 12, 1944, Serial No. 558,320

3 Claims. (Cl. 155—77)

1

This invention relates to chairs, and particularly to reclining chairs of the type ordinarily referred to as lounge chairs.

The principal object of this invention is to provide a sturdy and comfortable chair that has a pleasing and attractive appearance.

Another object is to provide a chair of the type mentioned which is noiseless, simple to use and which will be inexpensive to manufacture.

These and other objects and features of the invention will become apparent from a reading of the following description and claims, together with the accompanying drawing, in which like parts are referred to and indicated by like reference characters and wherein:

Figure 1 is a side elevation of a chair embodying the instant invention;

Figure 2 is a bottom view of a chair frame;

Figure 3 is an enlarged vertical sectional view of one side of the chair frame, taken along the line and in the direction of the arrows 3—3 of the Figure 1; and

Figure 4 is an enlarged elevational view of the inside part of the chair frame, partly in section, taken along the line and in the direction of the arrows 4—4 of the Figure 2.

A chair made in accordance with this invention consists broadly of two main elements. There is first the stationary base consisting of spaced side elements, and second, the reclineable seat portion pivotally mounted on the base elements. Each of these two parts will be described in detail hereinafter and in the order just set forth.

The stationary base 11 of this chair consists of two pieces of wood, each of which is somewhat "U" shaped and provided with forward and rearward legs 12. The respective legs of each of the left and right side base elements are aligned laterally. The base elements have central transverse holes 15 therethrough which are aligned and which receive the individual pivot pins 16 hereinafter described. Each base element also has a convex portion 13 immediately above the aforesaid hole 15 which provides lateral support for the chair. The curved top horizontal surface or edge of the convex portion 13 is referred to and indicated herein as the rail portion 14 and is accurately curved around the center of the hole 15. This rail portion 14 also extends forwardly and rearwardly to the two legs 12.

The reclining seat consists of a rectangular frame formed of two pairs of parallel horizontal side rails connected together at their ends by front and rear transverse frame members 26 and

27. The two front corners of the rectangular frame have depending legs 28 thereon, as shown in the drawing. These prevent the reclineable seat member from tipping too far forward and 5 also enable the chair seat to assume a normal horizontal position when unoccupied. The chair frame also has an ascending rear back portion 29 and two arm portions connected thereto in a conventional manner. The two bottom side rails 10 22 are provided with holes that are aligned with the aforesaid holes 15 in the stationary base members and also receive the pivot pins 16 heretofore mentioned.

On the inner sides of the two top rails 23, near 15 the rear portion thereof and directly over the two aforesaid base elements 11, there are mounted two pieces of wood that are referred to herein as channeled portions and which are indicated in the drawing of the character 24. These are attached to the upper rails 23 by means of screws 20 as shown in the Figures 2, 3 and 4. Each channeled portion 24 has a bottom arcuate or concave edge that is slightly above the convex edge of its adjacent rail portion 14. The arcuate 20 concave portions center at the pivot pin 16, are concentric with and are spaced about one-quarter of an inch from the arcuately curved rail portions 14. There is absolutely no friction between nor 25 contact by the two facing edge surfaces. Each 30 of the channeled portions 24 has a depending flange 25 thereon which engages the inner side surface of the adjacent base element 11. The two rear lower corners of each of the channeled members 24 are spaced sufficiently above the 35 respective adjacent legs 12 so that the seat member may be free to tilt rearwardly, as indicated by the broken lines in the Figures 1 and 4 of the drawing.

As heretofore stated, the seat members and the 40 base elements are pivotally attached together at the aforesaid aligned holes on both sides of the chair, by means of the pivot pin 16. These two pivot pins 16 extend inwardly as is shown in the Figures 2 and 3 and each is provided with a small 45 washer 19 which abuts the inner side surface of the respective base element 11. Next, there is mounted on each pin a coil spring 17 and a fastening nut 18. The tension of the spring 17 may be increased or decreased by the rotation or the 50 positioning of the nut. However, the tension of the spring 17 should be sufficient to eliminate all unnecessary play between the two base elements 11 and the respective adjacent side rails 22 and 23 and so that the flanges 25 of the channeled 55 portions will smoothly engage, without binding.

the top inner side wall surfaces of the convex portions 13 of the base elements, as is indicated in the Figure 3 of the drawing.

The pivot 16 should be positioned nearer to the rear of the frame than to the front; about three-quarters of the way back is found to be satisfactory. At this location, it becomes natural and easy for an occupant to tilt the chair to a reclining position and this location of the pivots causes the greater weight of the chair to be forward of the pivot, and thus the chair is retained in its normal or upright position.

Among the many advantages that this chair has over prior art reclining chairs is the feature which makes it practically noiseless. Practically the full weight of the seat member and an occupant is borne by and concentrated at the two pivot pins, and there are no wood surfaces that rub against each other under weight which, under certain atmospheric conditions, become noisy. Furthermore, it has relatively few moving parts that are likely to wear and get out of order. It needs no lubrication, reduces to a minimum frictional contacts, and eliminates entirely loose parts such as rollers which rattle and often fall out of place when the chair is picked up or moved.

Only the preferred form of the invention has been described and illustrated herein. However, it is to be understood that the embodiment of the invention as set forth is suggestive only and is not to be considered in a limiting sense. Many changes may be made in the arrangement of the elements as shown and described, and other uses may be found for the invention. These changes and modifications should also be considered as coming within the scope of the appended claims. Therefore, without limiting myself to the precise structure illustrated and described, I claim:

1. In a reclining chair, a base member having a first pivot hole therethrough and including a first friction surface perpendicular to the said pivot hole and a convex top concentric with the said pivot hole, a seat member having a second pivot hole therethrough aligned with the aforesaid first pivot hole, said seat member also having a lateral portion having a concave bottom concentric with the convex top and spaced therefrom and including a second friction surface perpendicular to the said pivot hole and frictionally engageable with the said first friction surface, the said lateral portion also having a depending flange adjacent to the said bottom portion and slidably engageable with the said base member, a pivot pin mounted in the aforesaid pivot holes retaining the aforesaid members in alignment, and adjustable compression means mounted on the said pivot pin for regulating the degree of frictional engagement between the said first and second friction surfaces.

2. In a reclining chair, a base member having a first pivot hole therethrough and including a first friction surface perpendicular to the said pivot hole and a convex top concentric with the said pivot hole, a seat member having a second pivot hole therethrough aligned with the aforesaid first pivot hole, said seat member also having a lateral portion having a concave bottom concentric with the convex top and spaced therefrom and including a second friction surface perpendicular to the said pivot hole

and frictionally engageable with the said first friction surface, the said lateral portion also having a depending flange adjacent to the said bottom portion and slidably engageable with the said base member, a pivot pin mounted in the aforesaid pivot holes retaining the aforesaid members in alignment, a helical spring laterally mounted on the said pivot pin, in engagement with the said base member, and a compression adjusting nut mounted on the said pivot pin, co-operating with the said helical spring and capable of varying the compression of said helical spring, whereby the degree of frictional engagement between the said first and second frictional surfaces can be regulated.

3. A reclining chair, comprising in combination, a pair of parallel base members, each having an inner and outer side wall and aligned pivot holes therethrough, the said outer side wall including a friction surface perpendicular to the said pivot hole, each of the said base members having an arcuate top edge concentric with the pivot holes, a seat member including back and arm portions and including parallel pairs of lower and upper side rails, each of the said side rails having an inner friction surface facing a base member friction surface, the lower side rails having pivot holes therethrough aligned with the aforesaid base member pivot holes, the upper side rails having lateral portions having arcuate bottom edges concentric with the aforesaid arcuate top edge of the base members and spaced therefrom, each of the said bottom edges having a depending flange slideably engageable with an adjacent base member inner side wall, pivot pins mounted in the aligned holes of adjacent base and seat members, and holding the said members in alignment, a helical spring co-axially mounted on each pivot pin, in engagement with the said base members, and a compression adjusting nut mounted on each of the said pivot pins co-operating with the said helical springs and capable of varying the compression of said helical springs, whereby the degree of frictional engagement between the said base and seat member frictional surfaces can be regulated.
